UNITED STATES PATENT OFFICE.

JOSEPH A. RAYMOND, OF CHICAGO, ILLINOIS.

COMBINED ESCUTCHEON AND HANDLE.

1,291,135.

Specification of Letters Patent. Patented Jan. 14, 1919.

Application filed December 26, 1917. Serial No. 208,894.

To all whom it may concern:

Be it known that I, JOSEPH A. RAYMOND, a citizen of the United States, and a resident of the city of Chicago, in the county 5 of Cook and State of Illinois, have invented certain new and useful Improvements in Combined Escutcheons and Handles, of which the following is a specification.

10 This invention relates to escutcheons and handle bars which are particularly adapted to be used on burial caskets, the escutcheons being secured to the casket and the handle bars pivotally attached to the escutcheons.

15 The objects of this invention are, to obtain improved appearance to the combined escutcheons and handle bars made from sheet metal, and to economize in the material required to obtain said escutcheons.

20 Further objects are to lessen the number of parts and diminish the liability of loss or breakage of said parts.

Additional objects are, to obtain a slightly 25 construction well adapted to perform the several functions which are required thereof and is durable.

Additional objects are disclosed in the specification and claims.

I have illustrated a combined escutcheon 30 and handle bar embodying this invention in the drawings accompanying and forming a part hereof, and in which—

Figure 1 is a front elevation, with the handle bar in its normal position.

35 Fig. 2 is an end elevation, with the handle bar in normal position.

Fig. 3 is an end elevation, with the handle bar in a raised and operable position.

Fig. 4 is a front elevation of a modified 40 handle bar.

Fig. 5 is a plan view of the blank illustrated with holes and recesses therein.

Fig. 6 is a vertical section of an end piece attachable to the ends of a handle bar of the 45 device.

Fig. 7 is a plan view of a blank from which the escutcheon member of the device is obtained.

Fig. 8 is a section of said escutcheon when 50 formed up, and

Fig. 9 is a rear elevation of said escutcheon and handle bar.

A reference character applied to designate a given part indicates said part throughout 55 the several figures of the drawing wherever the same appears.

A, represents an escutcheon blank which is provided with the holes a , a' . B, represents an escutcheon which is obtained from blank A. It will be observed that on the 60 forming up of the escutcheon B from the blank A the holes a are positioned in a part or member b of the escutcheon which is substantially at right angles to the base b' thereof, and are adapted to receive pivotal 65 member C. The holes a' are adapted to have screws or bolts D extend therethrough, to attach said escutcheon to a casket.

E is a blank of sheet metal, and, in the modified construction which is illustrated 70 in Fig. 4, is provided with the marks E', and in all the constructions illustrated, with tongues F, f, holes f', f' and slots or recesses f''.

Tongues F are formed up to obtain the 75 arm member G, having body parts g, and the sides g' g'. Holes f', f' are positioned in blank E so as to be located in sides g' and register with holes a; so that the hereinbefore mentioned pivot members C, when inserted in said holes a, a', are also inserted in holes f', f', to pivotally attach the members G, G, of the handle bar to the escutcheon. Holes a' are provided with annular flanges 80 a'' on the under side of the blank, which 85 form, on the upper side of said blank, recesses adapted to receive the heads of wood screws.

The cylinder I, which forms the body of the handle bar, has tongues f, f, in recesses, 90 adjacent to the base of the members G; and said recesses extend between the outer edges f''', f''' of slots or recesses f'', and are, respectively, obtained from the blank E.

The tongues f, f, in recesses between said 95 edges f''', f''' which receive said tongues, serve to position the meeting edges of the remainder of the cylindrical portion of the handle bar so that the same are not readily observable when the escutcheons are attached as hereinbefore recited. K are ornamental ends which are inserted in the ends of the cylindrical portion I of the handle bar, for appearance, and I do not, of course, confine myself to the form or shape of said 100 ends which is illustrated.

To assemble the combined escutcheon and handle bar the holes a in the escutcheons and f' in members G, are made to register and the pivotal members C are inserted in said 110 hole.

The escutcheons being secured to the sides

of a casket, or of a box or chest, the members 5 G will normally be substantially vertical, and to raise said casket by means of the handles said members G are turned, as by means of cylindrical portion I, on pivotal members C into substantially horizontal planes, at which time the upper surface or 10 face of said members G will contact with the edges L of the raised part of the escutcheon 15 which is positioned between sides b, b; said contact limiting the turning of said member G.

I claim;—

1. In combination, an escutcheon and a 15 handle bar pivotally attached thereto, said handle bar comprising a hollow sheet metal cylinder provided with longitudinally extending meeting edges and with tongues having integral side walls, extending outwardly from the wall of said cylinder with the body parts thereof substantially tangential thereto, said wall also having apertures extending from one of said meeting edges to 20

said tongues, and additional tongues extending from the other of said meeting edges and fitting in to close said apertures. 25

2. A handle bar comprising a hollow sheet metal cylinder having longitudinally extending meeting edges in the wall thereof and having tongues integral therewith, said 30 tongues being provided with integral side walls extending into said cylinder wall, the parts of said tongues between the side walls thereof being substantially tangential to said cylinder, said cylinder wall being provided with recesses extending from one of said meeting edges to said tongues to form apertures adjacent to said tongues, and provided with additional tongues extending from the other of said meeting edges to fit 35 in said apertures and close the same. 40

JOSEPH A. RAYMOND.

In the presence of—

CHARLES TURNER BROWN,
J. SCUDDER.
